UNITED STATES PATENT OFFICE.

ROBERT L. BROWN, OF MILWAUKEE, WISCONSIN, ASSIGNOR TO HARNISCHFEGER CORPORATION, OF MILWAUKEE, WISCONSIN, A CORPORATION OF WISCONSIN.

TRENCH-DIGGING MACHINE.

Application filed April 9, 1926. Serial No. 100,783.

This invention relates to improvements in trench or ditch digging machines of the so-called "ladder" type, and more particularly to an improved crowding and hoisting mechanism for the boom and excavating buckets carried thereby.

Machines of the character referred to comprise, in general, a frame mounted on wheels at the front end thereof and on a suitable tractor at the rear end of the same, a rearwardly extending boom pivotally connected to the frame and carrying rollers on which endless chains with buckets attached run, and suitable mechanism mounted on the frame for driving the machine forward, for operating the excavating buckets, and for raising and lowering the boom in accordance with the depth of the trench or ditch to be cut. Under favorable conditions, the weight of the boom and its associated parts is sufficient to hold the boom against the bank so that the excavating buckets will cut into the same and carry out the spoil. In some cases, however, such as when the ground is hard, it has been found that the weight of the boom and its associated parts is not sufficient to hold the same down and the excavating buckets in proper cutting position, the action of the boom being to rebound away from the bank upon engagement of the buckets with the obstruction.

One of the objects of the present invention, therefore, is to provide improved means providing for a crowding action for the boom and excavating buckets carried thereby whereby the latter are held in proper cutting position with respect to the bank, and wherein the boom is permitted to yield or rebound somewhat should the buckets strike an obstruction such as a boulder formation, service pipe, or the like.

Another object is to provide, in a machine of the character referred to, improved means for hoisting or adjusting the boom so that the tension or strain in the boom supporting cables on either side of the boom is equalized.

Another object is to provide, in a machine of the character referred to, improved means for providing for a crowding action for the boom and wherein such means may be readily disconnected if desired to permit the boom to rebound freely, or for any other reason.

Another object is to provide, in a machine of the character referred to, improved crowding and hoisting mechanism for the boom having advantages over such mechanism constructed heretofore as regards simplicity of construction and manner of operation.

Other objects and advantages will herein-after appear.

For the purpose of illustrating the invention an embodiment thereof is shown in the drawings, in which:

Figure 1 is a side elevational view of the rear end of a trench machine of the "ladder" type, showing the improved crowding and hoisting mechanism operatively associated therewith, the endless belt traction element being shown merely in dotted lines in order to better illustrate the crowding device.

Fig. 2 is an end elevation, looking toward the left in Fig. 1, some of the parts being removed;

Fig. 3 is a plan view of Fig. 1, some of the parts being removed;

Fig. 4 is an enlarged plan view of some of the parts comprising the crowding mechanism;

Fig. 5 is a front elevational view of Fig. 4;

Fig. 6 is a fragmentary plan view of the bolster forming part of the tractor frame; and

Fig. 7 is an elevational view, looking toward the left in Fig. 6.

The frame of the machine, designated generally by the reference numeral 1, is supported at its rear end by means of a suitable tractor 2 having a bolster 3 provided at one end with spaced lugs 4 and a downwardly extending lug 5, the respective ends of the bolster receiving and supporting the usual stub shafts 6 for driving and supporting the endless traction belts 7 and 8. A shaft 9 is supported by and journaled in any suitable manner in frame 1 and is provided with grooved hoist drums 10 and 11 and with grooved crowding drums 12 and 13 fixed to this shaft for rotation therewith. A pair of sheaves 14 and 14' and a second pair of sheaves 15 and 15' are loosely fitted on a shaft 16 supported by frame 1 and arranged as shown, while a pair of similar sheaves 17 and 17' and another pair of sheaves 18 and 18' are loosely mounted on a shaft 19 arranged transversely of boom 20 and secured

thereto in any suitable manner such as by brackets 19'. Sheaves 21 are arranged on either side of boom 20, as more clearly shown in Fig. 2, and are supported by means of 5 brackets 22 for rotation about axes transverse to shaft 19 or in other words, transverse to the axes of rotation of sheaves 17, 17', 18 and 18' mounted on shaft 19, brackets 22 being suspended from the frame member 10 23 through which shaft 16 extends.

Shaft 9 is driven or operated in either direction by means of a reversible drive shaft 24 connected to shaft 9 by means of a sprocket chain 25 and sprocket wheels 26 and 27 fixed 15 to these shafts, as more clearly shown in Figs. 1 and 3. A single cable 28 is anchored at one end to drum 10 and extends over sheave 14, downwardly and around sheave 17, upwardly and over sheaves 21, thence downwardly and around sheave 17', and thence upwardly and over sheave 14', cable 28 then extending to drum 11 and being anchored thereto. From the foregoing it will be seen that upon operation of shaft 9 in a counter-clockwise direction, as viewed in Fig. 1, the ends of cable 28 will be wound upon drums 10 and 11 to cause raising or upward movement of boom 20 and its associated parts about shaft 29, by means of which latter 25 shaft the boom is pivotally connected to frame 1, and that upon reverse operation or rotation of shaft 9 the boom will be lowered. The use of sheaves 21 and the manner in which they are arranged permit of the use of a single 30 cable for raising and lowering the boom, this providing for equalized suspension of the boom on either side thereof.

A sheave 30, mounted in a suitable housing 31, is arranged on one side of the machine as 40 shown and is pivotally connected to lugs 4 by means of a pin 32. A bolt 33 extends longitudinally of the machine and loosely through lug 5, and is pivotally connected to housing 31 by means of a pin 34, a coiled 45 spring 35 being arranged on the bolt between lug 5 and nuts 36 threaded on the end of the bolt.

A cable 37 is fixed at one end to drum 12 50 and extends over sheave 15 and downwardly and around sheave 30, and thence around sheave 18 and back toward sheave 30, cable 37 at this point being pivotally connected to housing 31 by any suitable means such as the 55 U-shaped strap 38 having its ends loosely fitting over the extended ends of shaft 39 extending through housing 31 and upon which sheave 30 rotates.

A second cable 40 is fixed at one end to drum 13 and extends over sheave 15' and 60 downwardly and around a sheave 30' similar to and supported in the same manner as sheave 30, and thence around sheave 18' and back toward sheave 30', the cable being secured at this point to the shaft of sheave 65 30' in the same manner as the corresponding

end of cable 37 is secured to shaft 39 of sheave 30.

As more clearly shown in Fig. 1, the arrangement is such that upon rotation of shaft 9 in a counter-clockwise direction, the ends 70 of the single cable 28 will be wound up a certain amount on the hoisting drums 10 and 11 to cause raising of the boom, while the cables 37 and 40 will be unwound or payed out this same amount from the crowding drums 75 12 and 13 so that the boom and its associated parts are permitted to be raised by means of cable 28. Upon reverse rotation of shaft 9, the ends of the single cable 28 are unwound or payed out from the hoisting drums 10 and 80 11 to permit the boom and its associated parts to drop by their own weight to a position desired, cables 37 and 40, at this time, being pulled in or wound up this same amount upon the crowding drums 12 and 13 so that 85 for all positions of adjustment of the boom the same is yieldingly held in cutting position and against rebounding or movement away from the bank by cables 37 and 40 and cooperating parts. The boom is thus adjusted 90 according to the depth of the trench or ditch to the dug, and shaft 9 held in any suitable manner against movement in either direction until the next adjustment is to be made. In the event that one of the buckets 95 41 strikes an obstruction such as a boulder or service pipe, the boom will rebound away from the bank, with a corresponding increase in the tension of cables 37 and 40, this being accompanied by pivotal movement of the 100 sheave housing 31 about pins 32 and further compression of springs 35 between lugs 5 and the stops or nuts 36. Springs 35 thus provide for a yieldable crowding action on the boom whereby the latter is permitted to give or 105 rebound to some extent when the buckets encounter an extraordinary obstruction, the springs acting to return the boom to its normal position after the obstruction has been passed.

During operation of the machine, the tension in springs 35, caused by their compression between lugs 5 and nuts 36, maintain such tension in cables 37 and 40 that the boom and buckets carried thereby are crowded or 115 held into the bank with sufficient force to provide for proper cutting action under conditions usually encountered. To meet varying conditions, such as for instance where the ground is very hard, nuts 36 may be adjusted on bolts 33 to cause greater initial compression of springs 35 and corresponding greater tension in cables 37 and 40 and greater crowding action on the boom and buckets. Adjustment of nuts 36 toward the ends of 125 bolts 33 will, of course, produce the opposite effect, and result in less crowding action on the boom and buckets. Such an adjustment may be advantageous in working in comparatively soft or loose dirt. If it is desired to 130

eliminate the crowding action of springs 35 and the associated parts, cables 37 and 40 may be disconnected by removing pins 42 or by disconnecting the ends of these cables from the crowding drums 12 and 13.

From the foregoing it will be seen that improved hoisting and crowding mechanism for trenching machines of the "ladder" type has been provided which is simple in construction and manner of operation, and which may be adjusted to meet varying conditions.

While one embodiment of the invention has been shown and described, it is to be understood, of course, that various changes in the size, shape and arrangement of the parts may be adopted without departing from the spirit of the invention or the scope of the claims.

The invention claimed is:

1. In a machine of the character described, the combination with the frame and boom thereof, and an operating shaft mounted on said frame, of a first cable operatively connected to said boom and extending upwardly therefrom and connected to said shaft for winding thereabout upon rotation of the same in a given direction to effect raising of said boom, and a second cable operatively connected to said boom and extending downwardly therefrom and connected to said shaft for winding thereabout upon rotation of the same in the opposite direction to urge said boom downwardly toward the work.

2. In a machine of the character described, the combination with the frame and boom thereof, and an operating shaft mounted on said frame, of a first cable operatively connected to said boom and extending upwardly therefrom and connected to said shaft for winding thereabout upon rotation of the same in a given direction to effect raising of said boom, a second cable operatively connected to said boom and extending downwardly therefrom and connected to said shaft for winding thereabout upon rotation of the same in the opposite direction to urge said boom downwardly toward the work, and yielding means operatively associated with said second cable.

3. In a machine of the character described, the combination with the frame and boom thereof, of an operating shaft mounted on said frame, a plurality of drums fixed on said shaft, a first cable operatively connected to said boom and extending upwardly therefrom and being fixed at one end to one of said drums for winding thereon upon rotation of said shaft in one direction to effect raising of said boom, and a second cable operatively connected to said boom and extending downwardly therefrom and being fixed at one end to another of said drums for winding thereon upon rotation of said shaft in the opposite direction to urge said boom downwardly toward the work.

4. In a machine of the character described,

the combination with the frame and boom thereof, of an operating shaft mounted on said frame, a plurality of drums fixed on said shaft, a first cable operatively connected to said boom and extending upwardly therefrom and being fixed at one end to one of said drums for winding thereon upon rotation of said shaft in one direction to effect raising of said boom, a second cable operatively connected to said boom and extending downwardly therefrom and being fixed at one end to another of said drums for winding thereon upon rotation of said shaft in the opposite direction to urge said boom downwardly toward the work, and spring means operatively associated with said second cable for yieldingly opposing upward movement of said boom away from the work.

5. In a machine of the character described, the combination with the frame and boom thereof, of a first and a second sheave carried by said boom for rotation about a common axis, an operating shaft mounted on said frame, a first cable trained about said first sheave and extending upwardly therefrom and being connected to said shaft for winding thereabout upon rotation of the same in a given direction to effect raising of said boom, and a second cable trained about said second sheave and extending downwardly therefrom and being connected to said shaft for winding thereabout upon rotation of the same in the opposite direction to urge said boom downwardly toward the work.

6. In a machine of the character described, the combination with the frame and boom thereof, of a first and a second sheave carried by said boom for rotation about a common axis, an operating shaft mounted on said frame, a first cable trained about said first sheave and extending upwardly therefrom and being connected to said shaft for winding thereabout upon rotation of the same in a given direction to effect raising of said boom, a second cable trained about said second sheave and extending downwardly therefrom and being connected to said shaft for winding thereabout upon rotation of the same in the opposite direction to urge said boom downwardly toward the work, a third sheave associated with said frame and supported for pivotal movement with respect thereto and arranged below said second sheave, said second cable being trained also about said third sheave, and spring means associated with said third sheave and acting thereon to restrain said movement of the latter in one direction.

7. In a machine of the character described, the combination with the frame and boom thereof, of a member associated with said frame and provided with an apertured lug, a housing pivotally connected to said member, a sheave arranged and journaled in said housing, a bolt extending loosely through said lug

- and provided at one end with a stop and connected at its other end to said housing, a spring arranged on said bolt between said lug and said stop, an operating shaft mounted on said frame, a cable operatively connected to said boom at a point above said sheave and being trained about the latter and connected to said shaft for winding thereabout upon rotation of the same in a given direction to urge said boom downwardly toward the work and to cause compression of said spring between said lug and said stop, and means for raising said boom.
8. In a machine of the character described, the combination with the frame and boom thereof, of a member associated with said frame and provided with an apertured lug, a housing pivotally connected to said member, a sheave arranged and journaled in said housing, a bolt extending loosely through said lug and provided at one end with a stop and connected at its other end to said housing, a spring arranged on said bolt between said lug and said stop, an operating shaft mounted on said frame, a cable operatively connected to said boom at a point above said sheave and being trained about the latter and connected to said shaft for winding thereabout upon rotation of the same in a given direction to urge said boom downwardly toward the work and to cause compression of said spring between said lug and said stop, and means for raising said boom, said means being connected to said shaft for operation thereby upon rotation of the same in the opposite direction.
9. In a machine of the character described, the combination with the frame and boom thereof, and an operating shaft mounted on said frame, of cable means operatively connected to said shaft and boom, a sheave engaging said cable means to cause the same to exert an upward pull on said boom upon operation of said shaft in one direction, second cable means operatively connected to said shaft and boom, and a sheave engaging said second cable means to cause the same to exert a downward pull on said boom upon operation of said shaft in the opposite direction.
10. In a machine of the character described, the combination with the frame and boom thereof, and an operating shaft mounted on said frame, of first cable means connected to said boom and extending upwardly therefrom, and second cable means connected to said boom and extending downwardly therefrom, said first and second cable means being connected to said shaft to effect pulling in on said first cable means to raise said boom and simultaneous paying out of said second cable means upon operation of said shaft in one direction and to effect pulling in on said second cable means to urge said boom toward the work and simultaneous paying out of said

first cable means upon operation of said shaft in the opposite direction.

11. In a machine of the character described, the combination with the frame and boom thereof, and adjusting means for said boom, of a bolt provided at one end thereof with a stop and extending longitudinally of said frame, means for guiding and supporting said bolt, a drive shaft, cable means operatively connected to said shaft and said bolt and said boom and extending downwardly from the latter whereby the same and its associated parts are moved toward the work upon operation of said shaft in one direction, and a spring arranged on said bolt being said first-named means and said stop for yieldingly holding said boom in cutting position.

12. In a machine of the character described, the combination with the frame and boom thereof, and adjusting means for said boom, of a sheave, means supporting said sheave for pivotal movement with respect to said frame, a drum mounted on said frame, a sheave carried by said boom and arranged above said first-named sheave, a flexible element fixed at one end to said drum and trained about said sheaves and fixed at its other end to said sheave-supporting means, and means for operating said drum to wind up said element thereon to effect crowding of said boom and its associated parts toward the work.

13. In a machine of the character described, the combination with the frame and boom thereof, and adjusting means for said boom, of a sheave, means supporting said sheave for pivotal movement with respect to said frame, a drum mounted on said frame, a sheave carried by said boom and arranged above said first-named sheave, a flexible element fixed at one end to said drum and trained about said sheaves and fixed at its other end to said sheave-supporting means, means for operating said drum to wind up said element thereon to effect crowding of said boom and its associated parts toward the work, and a spring acting on said sheave-supporting means to restrain said pivotal movement thereof in one direction.

14. In a ladder type trenching machine, the combination with the boom thereof, of cable means for lifting said boom, cable means for urging the boom to its work, and means for simultaneously adjusting both said cable means in such wise that the tension of the second-named cable means is maintained substantially constant for all positions of the boom.

15. In a ladder type trenching machine, the combination with the boom thereof, of cable means for lifting said boom, cable means for urging the boom to its work, means for simultaneously adjusting both said cable means in

such wise that the tension of the second-named cable means is maintained substantially constant for all positions of the boom, and a yielding connection interposed in said 5 second-named cable means.

16. In a ladder type trenching machine, the combination with the boom thereof, of a yieldingly supported sheave mounted on said machine to the rear of said boom, a hoisting shaft, a plurality of cables associated therewith for reverse winding with respect thereto, one connected with the boom for raising the latter and the other passing over said sheave and connected with the boom for holding the 15 latter to its work.

17. In a ladder type trenching machine, the combination with the boom thereof, of a yieldingly supported sheave mounted on said machine to the rear of said boom, hoisting 20 means, a cable for urging the boom to its work connected to said boom and passing rearwardly and over said sheave and then to the hoisting means, a cable for hoisting the boom connected to the latter and passing upwardly therefrom and to the hoisting means, 25 said cables being arranged for relatively opposite travel upon operation of said hoisting means whereby the tension of said first-named

cable is maintained substantially constant for all positions of the boom.

18. A ladder type trenching machine including a boom, a flexible element operatively connected to the boom for positively lifting the same, a second and separate flexible element operatively connected with the boom for urging the boom toward its work, and a yieldable means associated with the second flexible element for permitting the boom to partake of limited movement away from its work when subjected to predetermined 40 stresses.

19. A ladder type trenching machine including a boom, a flexible element operatively connected to the boom for positively lifting the same, a second and separate flexible element operatively connected with the boom for urging the boom toward its work, and a yieldable means associated with the second flexible element for permitting the boom to partake of limited movement away from its work 45 when subjected to predetermined stresses, and means for simultaneously and reversely operating the flexible elements.

In witness whereof I hereto affix my signature.

ROBERT L. BROWN.
